FUEL SUPPLY DEVICE FOR INTERNAL COMBUSTION ENGINES

Irven E. Coffey, St. Louis, Mo., assignor to Carter Carburetor Corporation, St. Louis, Mo., a corporation of Delaware

Original application January 28, 1932, Serial No. 589,436. Divided and this application July 23, 1936, Serial No. 92,133

16 Claims. (Cl. 123—119)

My invention relates to an improvement in the fuel supply for an internal combustion engine for the initial starting of a cold engine, and applies to the type in which a liquid fuel is vaporized or gasified before entering the engine cylinders.

This is a division of a copending application in the name of the present inventor, Serial No. 589,436, filed January 28, 1932, which has matured to Patent No. 2,116,596, granted May 10, 1938.

10 In the present practice of starting cold engines, an electric starting motor is used to rotate the crank shaft and reciprocate the pistons for creating a suction to draw fuel into such cylinders for the carburetor. In order to increase the flow of fuel, it is usually the practice to use a choke on the air intake which functions to increase, to a great extent, the amount of liquid fuel in proportion to the air. Usually the choke must be maintained more or less closed until the engine 15 becomes heated increasing the suction applied to the fuel nozzle, but decreasing the air available for mixing with the gasoline vapor. The resulting mixture is abnormally rich in gasoline, much of which is not properly gasified or recondensed before reaching the inlet ports. Thus, a wet mixture is drawn into the cylinders, and this washes the lubricating oil from the cylinder walls and passes the pistons, diluting the crank case lubricating oil. Attempts have been made to 20 remedy this defect by installation of electric heating elements in the intake manifold, but it is necessary to heat a large proportion of air compared with the amount of vaporized fuel; therefore, these heaters are inefficient. Where the 25 choke is automatically operated, fuel is drawn into the cylinders even if, through inadvertence, the ignition switch is not turned to the closed circuit position, in which case the engine usually becomes flooded with the condensed fuel.

30 A main object and feature of my invention is at the same time the starting motor is energized to turn over the engine for starting, to inject an auxiliary supply of fuel, preferably from the carburetor, into the intake manifold, and to heat 35 this fuel as it is atomized and vaporized, the heating, in the present instance, being done by an electrical heating element. In addition, I provide an auxiliary air supply which functions to carry the fuel which is gasified by heat, and thus 40 provide a dry gas with heated air for the initial starting of the engine.

45 After the engine has been initially started and the starting motor no longer functions, and also the electrical heat is discontinued, I provide an auxiliary fuel supply with additional air to carry

such vaporized and gasified fuel. This forms a secondary object and feature of my invention.

A third feature of my invention is the provision of a thermostatic control for the secondary auxiliary supply whereby when the engine becomes sufficiently hot to draw the fuel from the carburetor in a normal manner, the auxiliary fuel supply and the auxiliary air is cut off and maintained in a cut off condition while the engine is running at its normal operating temperatures. 10 However, the thermostatic control is operative so that should the engine cool to such an extent as to possibly make the starting difficult, the auxiliary fuel supply will come into operation with the auxiliary air to carry such supply, and 15 on use of the starting motor, electrical heat will be supplied to the auxiliary fuel and auxiliary air. In one form of my invention, the hot gasified fuel is fed without the auxiliary air direct into the intake manifold. 20

An important feature of my invention is that if the engine is at a sufficient temperature to operate directly from the fuel drawn through the carburetor on starting, although the electric heating element will be automatically heated, there 25 will be no auxiliary gas or air supply drawn through the heating device.

The operation of my invention may be accomplished in various forms of appliances which may be installed on engines now in use, or may be 30 built into new installations.

My invention is illustrated in connection with the accompanying drawings, in which:

Figure 1 is a diagrammatic illustration of the fuel supply and starting system of the engine with 35 my auxiliary fuel device illustrated in elevation;

Figure 2 is a vertical section through my auxiliary fuel device;

Figure 3 is a detail horizontal section on the line 3—3 of Figure 2 viewed in the direction of 40 the arrows;

Figure 4 is a detail horizontal section on the line 4—4 of Figure 2 viewed in the direction of the arrows;

Figure 5 is a diagrammatic illustration of an 45 other adaptation of my invention;

Figure 6 is a vertical section through the alternative form of my invention illustrated in Figure 5;

Figure 7 is an enlarged vertical section of the 50 piston, needle valve, and air control;

Figure 8 is a detail horizontal section on the line 8—8 of Figure 7 viewed in the direction of the arrows;

Figure 9 is a detail horizontal section on the 55

line 9-9 of Figure 7 viewed in the direction of the arrows.

Referring first to the illustration of Figure 1, the engine block with the engine cylinders is indicated by the numeral 11, the intake manifold 12, the exhaust manifold by 13, the carburetor by 14, such carburetor being indicated as having a choke valve 15 and a throttle valve 16, these latter being of conventional type. While the carburetor is illustrated as of the up-draft type, my invention applies equally to a downdraft type of carburetor.

The starting system indicates a starting motor 17 and a starting switch 18. This is illustrated as having a bridging piece 19 which connects to the contact points 20 and 21. The contact 20 is indicated as having a lead 22 to the storage battery 23, such being a source of supply, the negative side of this battery being grounded at 24. The contact 21 has a lead 25 to the terminal 26 of the starting motor.

Referring particularly to the device of my invention shown in detail in Figures 2, 3, and 4, I employ a casing structure 27 which may be attached to the engine block in any suitable manner or, if desired, supported from the carburetor. This has a cylinder 28 therein which is preferably made of brass. A closure plug 29 is screwed into the lower end of the cylinder and has a packing gasket 30 engaging the case and forming a liquid-tight seal. A fuel supply pipe 31 is connected to a nipple 32 at the lower end of the plug. This plug is provided with a large bore 34 receiving ball valve 37 and an apertured, threaded insert 35 forming a seat for ball check 37. A pin 38 limits the upward movement of the ball. A smaller bore 39 leads through the upper portion of plug 29 into the fuel chamber 40.

The fuel pump comprises a loose fitting cylinder or plunger 41 preferably having a number of vertical grooves 42. Plunger 41 has a recess 43 at the bottom receiving compression spring 44 seated against plug 29 and urging the plunger upwardly. A diaphragm 45 is attached at its periphery to the connecting flanges 46 of the case, the case 45 thus having a sealed lower and upper section. The center portion of the diaphragm bears on a shoulder 47 on piston plunger 41. A nut 48a threaded on the nipple 49 clamps the center portion of the diaphragm and is itself held in position by a lock nut 50. Nut 48a has a plurality of axially projecting fingers 51. Plunger 41 has a central fuel duct 52 communicating at the top with a small tube 53 having a valve seat 54 at its upper extremity.

55 Casing 27 has a cylindrical, upwardly projecting portion 55 with a tube 56 extending thereabove. This tube has a head 57 in which is threaded the plug 58 to which is connected the stem 59 of the needle valve 60 operating in connection with valve seat 54. A knurled head 61 allows adjustment of the stem and, hence, of the needle with reference to the valve seat. A nipple 62 on tube 56 is connected to a fuel pipe 63 which leads to the intake manifold 64, preferably, but not necessarily, posterior to the throttle 16.

Air enters casing 27 through pipe 65 having its outer end exposed to atmosphere and forming a heating coil 66 around the exhaust manifold. A rotary air valve, generally indicated at 67, in the part 55 of the casing has a cylindrical side wall 68, a bottom closure plate 69, and a top plate 70 having a depending apertured boss 71 through which the stem 59 of the needle valve extends. Top 70 is provided with a series of ports 72 disposed to register with ports 73 in the top 74 of

casing portion 55. Side wall 68 is provided with one or more circumferential slots 75, through which extend stop screws as at 76 for limiting rotation of the valve and also supporting the valve in casing portion 55. A relatively small cylinder 78 extends upwardly from central recess 77 in bottom plate 69 of the air valve. Cylinder 78 is inwardly flanged at its upper end as at 79, there being a small annular opening 80 between this flange and the tube 53, which carries the seat 54 of the needle valve.

The electrical system employs a solenoid 81, the winding of which is indicated as being on the outside of the cylinder 28 in the lower portion of the case 27. An electrical heating coil 82 is mounted in the air valve 67 and at one end is secured, as at 84, to a terminal 83 in cylindrical wall 68, and at the other end is connected to the boss 71 as at 85. Thus, the heating coil may rotate with the air valve. The thermostatic control is by means of a bimetallic thermostatic strip 86, which is arranged in the form of a spiral, one end being connected at 87 to the insulated terminal 83 on the outside of the valve 67. The opposite end has an outwardly bent finger 88 which operates between the contact 89 of terminal 90, and the stop 91 limiting the movement of the free outer end of the thermostatic strip. Current is supplied to the solenoid by means of a lead 92 connecting terminal 93 with either the 30 starter switch 19 or the ignition switch 98, as determined by selector 92'. The other terminal 94 of the solenoid is connected with thermostat terminal 90 by a lead 95. Switch 98 controls the usual ignition circuit, a part of which is indicated at 99. The auxiliary selector switch 92' may be omitted, if desired, and the thermostat and heating coil 82 connected permanently with either the starter or the ignition switch according to the length of time it is desired the thermostat and coil be heated electrically.

In my invention the chamber below the diaphragm designated 96 may be considered with the chamber 40 as the fuel chamber, because the device is installed at substantially the level of the fuel in the carburetor so that the fuel seeking its own level will rise past the check valve 33 and into the fuel duct 52. The arrangement, however, must be such that the needle valve seat 54 is never below the level at which the fuel would rise 50 in the auxiliary fuel device when the liquid seeks its own level. The upper part of the chamber 97 above the diaphragm may be considered as the air chamber.

The manner of operation and functioning of my device is substantially as follows:

When the ignition switch is closed and the selector switch 92' connected either to the starter switch or to the ignition switch, the current flow is by lead 92 to terminal 93, through solenoid 60 winding 81, terminal 94, lead 95, terminal 90 to contacts 88 and 89, which are closed when thermostat coil 86 is cold, and from terminal connection 83 to heating element 82 and ground at 85. The current through thermostat 86 heats 65 and expands the same, which, together with the heated air drawn from around the exhaust manifold at 66 through pipe 65 causes the thermostat to actuate the air valve 67 and also to open contact at 88.

Assuming the engine is cold and no current supplied to lead 92, the compression spring 44 maintains plunger 41 in an elevated position, with fingers 51 engaging the bottom plate 69 of the rotatable air valve 67 and the needle valve sub- 75

stantially restricted and ports 72 and 73 in registry. The thermostatic strip is cold so that the free end 88 thereof is in contact with the contact point 89 of the terminal 90. Under these 5 conditions, chamber 40 below the plunger 41 and chamber 96 below the diaphragm are filled with liquid fuel.

When the starting switches are closed, circuits 10 are completed to the starting motor, which rotates the crank shaft and reciprocates the pistons, and to the ignition. At the same instant the solenoid 81 is energized and a current is conducted through the bimetallic thermostatic strips to the heating coil 82, which is designed to substantially 15 instantly become hot. The solenoid exerts an attraction on the cylinder or plunger 41, which functions as the armature of the solenoid, and draws this downwardly opening the needle valve, this action also pulling down on the diaphragm, causing this portion of the device to operate as a pump and force the liquid fuel in the 20 chambers 40 and 96 upwardly through the liquid duct 52 and through the needle valve at the top of the tube 53 where the fine atomized fuel immediately comes into contact with the heating coil 82. As the pistons are reciprocating, they create a suction in the intake manifold, but as the auxiliary fuel pipe 63 is connected below the throttle valve, that is, on the carburetor side 25 of such valve, there is but a slight suction applied to the fuel in casing portion 55. This suction, however, is sufficient to draw atmospheric air thru the air pipe 65 into the chamber 97 and upwardly through the annular opening 80 surrounding the needle valve, causing an immediate mixture of the air and the fuel, both being subjected to the heating action of the coil 82. This heating action immediately changes the atomized liquid fuel into a dry gas which is drawn 30 through the intake manifold into the engine cylinders. This action takes place without the closing of the choke valve 15.

The secondary action of my device is after the engine is started and the starting switch 18 is opened, in which case the solenoid and heating coil are deenergized, assuming selector 92' is positioned to connect lead 92 with switch 19. Spring 44 then forces plunger 41 upwardly, again restricting the needle valve and reducing the supply 45 of auxiliary fuel. The auxiliary air with the reduced amount of liquid fuel is then drawn by suction through the ports 72 and 73 and the fuel pipe 63 into the intake manifold. This gas is not electrically heated, however. At the same 50 time the engine draws fuel directly from the carburetor and the exhaust manifold becomes heated, and by means of the heating coil 66 heats the air through the pipe 65. As the air becomes heated in the chamber 97, the thermostatic strip 55 86 is heated and expands so that the free end 88 moves from the contact end 89 of the terminal 90 and abuts against the stop 91. The further expansion of the thermostatic strip then causes the rotation of the valve 67, bringing the ports 60 72 and 73 out of registry and stopping the upward flow of air and vaporized fuel. In addition, the conduction of heat from the engine block tends to heat the thermostatic strip so that as long as the engine is running normally and drawing fuel from the carburetor with the engine hot, the ports 72 and 73 are maintained out of registry 65 and thus the valve 67 closed.

Should the engine stop and be started while the engine is still hot and the thermostatic strip 70 86 still hot, the circuit is broken at 88, 89 and,

hence, neither the solenoid nor the heating coil is energized and no auxiliary fuel fed to the engine.

In case the heat applied to the auxiliary mixture during cranking when starter switch 19 is 5 closed is insufficient, as may be the case, for instance in cold weather, selector 92' may be moved to connect the thermostat and heating coil with the ignition switch. Thereupon, the thermostat and coil 82 will be electrically heated until the 10 circuit is broken at 88, 89 due to expansion of the thermostat.

In the construction illustrated in Figures 5 through 9, the air valve control device, designated generally by the numeral 100, employs a cylinder 101 at the upper portion of which there is a solenoid 102 having a cover or case 103. A closure head 104 is secured to the top of the case, and in a large recess 105 there is threaded a tubular plug 106. This plug has a nipple 107 to which is connected a gasoline feed tube 108, this tube being indicated as connected to the carburetor at the base thereof, as at 109. A bottom closure 110 is connected to the lower end of the case 103 and connects to the cylinder 101. A sleeve 111 is 20 fitted on the lower portion of the cylinder and is retained in position by a ring 112 secured to the lower end of the cylinder 101. A piston 113 (note Figure 7) slides in the cylinder 101. This piston has a central bore 116 and a downwardly projecting portion 114 with a relatively small bore 115. A fixed fuel and air tube 117 extends through the bores 115 and 116 rising to a considerable height above the piston, and this is retained in place by a screw threaded connection 30 118 with the lower part of the bore 115. The tube has a head 119 with wrench kerfs 120 and a downwardly extending sleeve 121.

The air control is by means of a rotatable sleeve 122 which is fitted over the upper end of the tube 117, this sleeve being contracted at the upper end 123. At the lower end of the sleeve, there is a cup 124 with an upwardly extending flange 125. This flange has an arcuate notch 126, into which extends a pin 127 fitted in the wall 45 of the piston. To this cup and at the bottom, there is secured the lower end of a helically wound bimetallic thermostatic strip 128. The upper end 129 of this strip is secured to the piston, preferably to the top. The tube 117 has a 50 series of ports 130, and the sleeve 122 has ports 131, these ports being adapted to align for flow of air. The air intake is by means of an air duct 132 through the top 104, there being an air tube 133 connected to this duct, and this air tube has 55 a heating coil 134 wound around the exhaust manifold. There is an air chamber 135 between the piston and the cover 104.

The piston is provided with counteracting or counterbalancing springs 136 and 142. Lower 60 spring 136 rests on a washer 137 connected to a ring 138 on the inside, and on the outside resting on a split ring 139 which fits in an annular groove 140 in the lower end of the cylinder 101. The upper end of the spring bears on the shoulder 141 of the piston. Above the piston there is a second spring 142 which at its lower end bears on the cup 124, and its upper end is seated in a recess 143 in the cap or cover 104. It is to be noted that the sleeve 111 is freely rotatable on the lower end of the cylinder 101 and it is provided with a wrench grip head 144 to effect this rotation for a purpose hereafter detailed. A packing washer 145 fits between the head 144 and the bottom plate 110.

The automatic heating arrangement utilizes a tubular housing designated generally by the numeral 146. This has an upper section 147 and lower section 151. Upper section 147 provides a relatively large chamber 148 and has a screw threaded connection 149 with the sleeve 111. A set screw 150 allows clamping together of these parts. Lower section 151 is screw threaded and threads into the intake manifold. An end plate 152 and spacers 154 are secured to the depending portion by pins 153. Spacers 154 provide a plurality of radial slots 155 communicating with the intake manifold. A packing gasket 156 is provided outside of the intake manifold. An electric heating coil 157 has its lower end 158 connected to the closure member 152 as a ground connection, and its upper end connected to a lead 159 and terminal 160 which extends through the wall of the upper section 147. An electric lead 161 extends from this terminal 160 and to one end 162 of the solenoid coil. The opposite end of this coil has a lead 163 which is illustrated as being connected to a lead 164 from the starting motor switch 19 to the connection 26 of the starting motor 17. Therefore, when the starting motor switch is closed to energize the starting motor, the solenoid is energized and also the heating coil.

The needle valve construction employs a valve seat 165 which is formed in the lower portion of fixed tube 115 and through this seat extends the needle point 166 on the stem 167. This stem is connected to a raised center portion 168 of the end plate 152. The needle may be adjusted as to its seat by loosening the set screw 150 and rotating the sleeve 111. As the structure 146 is held in a fixed position in the intake manifold and the upper part of the casing having the solenoid is held from rotation by its connection to the fuel supply and auxiliary air supply, the rotation of the sleeve 111 threads the upper part of the housing with the solenoid and the valve seat up and down with reference to the fixed housing 146. An initial adjustment may thus be obtained of the needle valve suitable for different engines.

The manner of operation and functioning of the device of Figures 5 through 9 is as follows:

Normally the ports 130 and 131 in the fixed tube 115 and the rotatable sleeve 122, respectively, are in the closed position when the engine is cold, that is, when the thermostatic strip is in the cold condition. This represents the position on starting the cold engine. Plunger 113, which fits loosely in its cylinder, is supported on the lower spring in an intermediate position and the needle valve is partly open. Sleeve 122 has a fairly close sliding fit in the tubular plug 106.

On closing the starter switch the engine is turned over by the starting motor creating a suction in the intake manifold through the carburetor, and at the same time the solenoid is energized and elevates the piston 113. This carries the valve seat away from the needle and further opens the needle valve. At the same time the heating coil 157 is energized and becomes hot. The suction of the engine quickly draws the liquid fuel upwardly through the pipe 108. This liquid fuel flows downwardly through the tube 115 and past the needle valve where it becomes atomized, and as the liquid fuel is subject to the hot wire coil 157 the drops of liquid fuel are immediately converted into a gas, which gas in expansion forces its way outwardly through the slots 155 into the intake manifold and is carried with the

intake air and any generated gas from the carburetor into the engine. The gas is too rich to be combustible by itself but on mixing with the intake air in the intake manifold develops an explosive mixture in the engine. As soon as the engine is started and operating under its fuel, the starting switch is opened, which deenergizes the solenoid and the electric heating coil. In this stage, however, the device will function to meter fuel to the engine. For instance, when the solenoid is deenergized, the piston returns to its normal position with the needle valve partly open. With the throttle nearly closed, the suction pulls the piston down, closing the needle valve to a greater extent, allowing but little fuel to pass such valve for economical operation; but when the throttle is opened wide, the piston is forced upwardly by the lower spring, thus opening the needle valve to a greater extent and allowing an increased injection of atomized liquid fuel into the intake manifold where it is mixed with the air and fuel vapor from the carburetor for power operation.

There is always a certain amount of air suction around the piston, which has a relatively loose fit, so that in all stages of operation there is an air flow through the air intake pipe 133 which has the heating coil 134, and as the air becomes heated, passing around the piston, which heats the thermostatic strip, which functions to obtain a rotation of the piston and sleeve 122 fitting over the tube 115, bringing ports 130 and 133 into registry. In addition, heat from the intake manifold itself is applied directly to the thermostat. Thus, when the engine becomes hot, there is an air circulation through the tube 133, the ports 131 and 130, and the slightly opened needle valve. This connection to atmosphere operates to break the vacuum in the fuel pipe 108 and, hence, no fuel is drawn upwardly into the auxiliary fuel supply device when the engine is running at normal temperatures. There is, however, a slight additional metered air supply to that in the intake manifold, for when the throttle is nearly closed, the suction on the piston maintains the needle valve nearly closed due to the increased vacuum in the intake manifold; but when the throttle is opened, the vacuum in the manifold is decreased and the piston elevates, opening the needle valve wider, thus allowing a greater inflow of air which has been preheated by the coil 134. Thus the device operates to function as an air metering device for operating the engine under normal conditions. When it is desired to start the engine while hot, the ports 130 and 131 are open so that on closing the starting motor switch, although the solenoid and heating coil are energized, no liquid fuel is drawn through the auxiliary fuel device, but only an additional flow of air.

It is believed obvious that my device may be made as part of a carburetor in both forms. The form of Figure 2 is illustrated as supported by the carburetor for direct connection to the intake manifold. It may be advisable in cold climates to connect the heating element with the ignition switch so that the heating coil may be maintained hot for a longer time. Therefore, in the construction of Figure 2, the heating coil would be maintained hot until the thermostatic strip opens the circuit. In the construction of Figure 2 when it is desired to pump additional charges of fuel, the switch controlling the solenoid after being opened may again be closed and this may be done a number of times until the

engine is running properly. I find that a suitable diaphragm may be made from fabric which is impregnated with varnish; this withstands the action of the gasoline.

5 A characteristic of my invention is that the fuel which is initially supplied in the liquid form becomes immediately converted into a gas which is a dry gas, and expands many times the volume of its form in a liquid, and this gas immediately 10 is taken into the intake manifold where it mixes with the air being taken into the engine. Also, the additional hot air supplied with the additional fuel forms a dry gas mixture. Therefore, if the engine does not immediately start, this 15 dry gas is pumped through the engine and will not condense.

The invention is not limited to the forms shown, but may be modified in various respects as will occur to those skilled in the art, and the 20 exclusive use of all such modifications as come within the scope of the appended claims is contemplated.

I claim:

1. In combination with an internal combustion 25 engine having a main fuel supply device, auxiliary fuel supply means including an atomizing pump, a heating element positioned to heat the atomized fuel discharged by said pump, an auxiliary air supply conduit, means for heating 30 the air supplied by said conduit, a thermostat exposed to air from said conduit, an air valve controlled by said thermostat, said thermostat retaining the valve open when the engine is cold and shutting the valve when the engine is hot 35 and thereby discontinuing the additional air supply when the engine operates at its normal running temperature, and means for conveying the auxiliary fuel and air supplies to the engine.

2. In a device of the class described, casing 40 structure having a diaphragm therein, a liquid fuel chamber on one side of said diaphragm, a solenoid having a movable armature connected to said diaphragm, a liquid fuel control valve operatively connected to said armature, an electric 45 heating coil, a common switch and circuit for the solenoid and the heating coil, means to flow liquid fuel into the fuel chamber on one side of said diaphragm, said armature being operative by energizing the solenoid to actuate the 50 diaphragm to force liquid fuel through the fuel valve into engagement with the heating coil, the heating coil being adapted to convert the liquid fuel to a gaseous fuel, and means to convey the gaseous fuel to the intake of an engine.

55 3. A device as described in claim 2 further including an air control valve mounted between the heating coil and the intake to the engine, an air supply pipe having means to heat the air passing through such pipe by the heat of the engine, and a thermostatic control device for such valve to open such valve when the engine is hot, said thermostatic control device being in circuit with the heating coil and having electrical connections to break the circuit through 60 the heating coil when the engine is hot.

4. In a device of the class described, tubular 70 structure having means for connection to an intake manifold of an engine, an opening in said structure for communicating with the interior of the manifold, a cylinder mounted on said structure, a solenoid surrounding said cylinder, a piston operating in said cylinder, a tube extending through said piston, a liquid fuel valve having a valve seat and a needle controlled by the movement of said piston, an electrical heating coil be-

low said piston, a liquid fuel intake connected above said cylinder and having an opening into the tube through said piston, and means to energize said solenoid and said electric heating coil, the energizing of the solenoid moving the piston 5 to open said valve whereby a suction on the intake manifold may introduce liquid fuel through the valve to the heating coil, said heating coil converting the liquid fuel to a gas and the gas being drawn into the manifold.

5. In a device as described in claim 4, an air supply having an air supply pipe with means to heat the air supplied thereby by the heat of the engine, a sleeve surrounding said tube in said piston, said tube and sleeve having ports adapted 10 to register to form an air supply to said needle valve, and a thermostatic control element operatively connected to said piston and sleeve to rotate said sleeve in accordance with the temperature of the engine, whereby on the engine becoming hot said ports are brought into registry so 15 as to thereby destroy the vacuum created through the needle valve and shut off the auxiliary fuel supply.

6. In a fuel supply device for an internal combustion engine having an intake passage, means forming a passage in which fuel and air are mixed, means for controlling the proportions in which said fuel and air are mixed, a suction operated device for varying the effect of said proportioning means, a heat responsive device for further affecting the operation of said proportioning means, and means for applying the heating effect of an electric current to said heat responsive device.

25 7. In a device of the class described, means forming a mixing passage in which liquid fuel and air are mixed, means operated by heat and by suction to vary the proportion in which said fuel and air are mixed, and means including a source 30 of electric current for supplying heat thereto.

8. In an internal combustion engine having an intake passage and an ignition switch, a device 40 for supplying a mixture of fuel and air to said intake passage, means including a bimetallic thermostat for varying the supply of fuel and air to said passage, a heating coil adjacent said bimetallic thermostat, and means controlled by 45 said ignition switch for passing electric current through said heating coil.

9. In an internal combustion engine having an intake passage, a device for supplying a mixture of fuel and air to said intake passage, said device being provided with a heat responsive device for modifying the supply of mixture to said passage, said device being further provided with an electric 50 heating coil capable of affecting the operation of said heat responsive device.

10. In an internal combustion engine having an intake passage, a device for supplying a mixture of fuel and air to said passage, said device including means operated by the suction of said intake passage to vary said mixture and a heat responsive device to further vary said mixture, and electric means for heating said heat responsive device.

11. In an internal combustion engine having an intake passage, a device for supplying a mixture of fuel and air to said passage, said device including means operated by the suction of said intake passage to vary said mixture and a heat responsive device to further vary said mixture, electric means for heating said heat responsive device, and means utilizing the heat of the engine to further influence said responsive device.

12. In combination with an engine having an intake manifold, a source of fuel supply, and a carburetor for supplying combustible mixture to said manifold, fuel supply mechanism including an electro-magnetic device for drawing fuel from said source, means for atomizing said fuel and conducting the same to said manifold, electrically actuated means for heating said fuel, means for the mixing of vaporized auxiliary fuel with an air supply, and means for controlling said air supply in accordance with the heat of the engine.
13. The combination of elements specified in claim 12 in which the fuel supply is controlled in accordance with the engine temperature.
14. In combination with an engine having an intake manifold, a liquid fuel supply, and a fuel providing device comprising electro-magnetic control means to draw fuel from said fuel supply, an electrical heating element, means to atomize the fuel and subject the same to said heating element for converting said auxiliary fuel to a gas, means to flow said gasified fuel to said intake manifold, means for mixing engine heated air with said fuel, and means for controlling

the fuel supplied by said device in accordance with the temperature of said air.

15. In a device of the class described, a liquid pump to provide an auxiliary liquid fuel supply for the engine, means to actuate said pump for priming the engine, an atomizer through which the pumped fuel is forced, means to heat the fuel discharged through said atomizer to convert the same to a gas, means to convey such gas to an associated engine, means for continuing the discharge from said device after said pump has become inactive, and means for controlling said continuing discharge substantially in accordance with engine conditions.

16. In a device as described in claim 15, an air supply for mixing with said auxiliary liquid fuel supply, and means for heating said air supply in accordance with the temperature of the associated engine, said controlling means constituting a thermostat operating in accordance with the temperature of said air supply and functioning to shut off said continuing discharge when the engine is at its normal running temperature.
